CLAIM

The ornamental design for a display screen or portion thereof with graphical user interface, as shown and described.

DESCRIPTION

DESCRIPTION

FIG. 1 is a front view of a display screen or portion thereof with graphical user interface showing our new design; FIG. 2 is another front view thereof showing only the claimed portion of FIG. 1 for the purpose of clarifying the details of the claimed subject matter;

FIG. 3 is another front view thereof showing the claimed subject matter of FIG. 1, but shown with an alternative broken line disclosure; and,

FIG. 4 is another front view thereof showing only the claimed portion of FIG. 3 for the purpose of clarifying the details of the claimed subject matter.

The outermost dash-dash broken lines in FIGS. 1 and 3 depict the display screen or portion thereof, and form no part of the claimed design.

The remaining dash-dash broken lines in FIGS. 1 and 3 show portions of the graphical user interface that form no part of the claimed design.
